(57) **CLAIM**

The ornamental design for a “impact socket,” as shown and described.

DESCRIPTION

FIG. 1 is a perspective view of a impact socket, showing my new design;

FIG. 2 is a front elevational view thereof;

FIG. 3 is a rear elevational view thereof;

FIG. 4 is a left side elevational view thereof

FIG. 5 is a right side elevational view thereof;

FIG. 6 is a top plan view thereof; and,

FIG. 7 is a bottom plan view thereof.

The broken line showing of an interior of the impact socket, within an innermost circular feature, and including a square drive end and a double square drive end, show unclaimed subject matter only and forms no part of the claimed design.
